[54] NICKEL ORGANIC COMPOSITIONS TO
IMPROVE DYEABILITY OF POLYMERS

[75] Inventor: Robert W. Murray, Lebanon, N.J.

[73] Assignee: American Cyanamid Company,
Stamford, Conn.wherein R and R' are independently C₁-C₈ alkyl; and
sulfonyl dialkylphenols of the formula

[21] Appl. No.: 12,978

[22] Filed: Feb. 21, 1979

[51] Int. Cl.² ..... D06P 5/00[52] U.S. Cl. 526/4; 8/4;
8/29; 8/168 D; 260/45.75 N; 260/429 R;
260/439 Rwherein R'' and R''' are independently C₁-C₁₂ alkyl are
used to provide polymer compositions which have im-
proved dyeability after exposure to high temperatures.
Preferably, the nickel salt of acetyl-acetone and 2,2'-sul-
fonylbis-(4-t-octylphenol) are reacted together and the
polymer is a polyolefin. Most preferably, the polyolefin
is polypropylene.
